UNITED STATES PATENT OFFICE.

FRANCIS W. GARTRELL, OF WASHINGTON, DISTRICT OF COLUMBIA, ASSIGNOR OF TWO-FIFTHS TO DONALD MCLEAN WALLACE, OF TAKOMA PARK, MARYLAND.

WALL-TIE.

1,114,251.

Specification of Letters Patent. Patented Oct. 20, 1914.

Application filed September 2, 1913. Serial No. 787,780.

To all whom it may concern:

Be it known that I, FRANCIS W. GARTRELL, a citizen of the United States, residing at Washington, in the District of Columbia, have invented new and useful Improvements in Wall-Ties, of which the following is a specification.

This invention relates to improvements in wall ties, and proposes a device which is especially useful as an anchorage connection between the adjoining sections of a double wall.

The principal object of the invention is to provide a wall tie of the character stated which may be used without entailing any interference with or departure from modern methods of wall construction, which provides an intrinsically strong connection between the adjoining wall sections, which embodies certain features whereby the wall sections may be anchored to one another at any desired points and without regard to the relative elevation of the courses of the bricks at such points, and in which the original intrinsic strength of the connection or anchorage is not reduced by reason of subsequent expansion or contraction of either or both of the adjoining wall sections.

A further object of the invention is to provide a wall tie of the character stated embodying certain features which make it especially advantageous in connection with walls which have adjoining sections of concrete and brick, *i. e.* concrete walls having a so-called brick or tile facing. The advantages of the tie in such environment reside not only in its intrinsic strength and its capacity for compensating for expansion or contraction of either or both of the adjoining wall sections, but also in the facility with which the tie may be applied during the construction of the wall.

Certain of the structural features whereby the tie is especially useful and advantageous in connection with brick or tile-faced concrete walls also render it of advantage in connection with walls composed wholly of bricks, *i. e.* walls in which several courses of bricks occupy a common horizontal plane.

50 A further object of the invention is to provide a wall tie of the character and

having the advantages stated which is of simple and durable construction and may be manufactured at relatively low cost.

Embodiments of the invention are illustrated in the accompanying drawings, in which:

Figure 1 is a sectional view showing a wall tie for uniting adjoining concrete and brick wall sections and showing the disposition of such tie during the formation of the concrete section; Fig. 2 is a similar view showing the parts of the tie in operative relation and showing the brick section in course of construction; Fig. 3 is a horizontal sectional view on the line 3—3 of Fig. 2; Fig. 4 is a perspective view of the tie *per se*, showing in dotted lines the outline of a shield (metal or composition) which is preferably employed; Figs. 1, 2, and 3 assume the use of a composition shield. Fig. 5 is a view similar to Fig. 1, but showing a slightly modified construction, the modification consisting in the use of a metallic shield; Fig. 6 is an elevation of the tie shown in Fig. 5, showing the same associated with a concrete wall section; Fig. 7 is a perspective view of a further modified construction which is especially applicable to walls composed wholly of brick.

Similar characters of reference designate corresponding parts throughout the several views.

The tie consists essentially of two members 1 and 2 for anchorage in the respective wall sections. In the forms shown in Figs. 1 and 5, the member 1 is for engagement with the concrete section A and the member 2 is for engagement with the brick section B.

The members 1 and 2 are formed of relatively stiff and heavy wire and are preferably of the construction shown according to which the member 1 has a pair of anchorage loops 3 connected by a straight bar 4, which, for convenience, will hereafter be referred to as a "shank" and the member 2 has a single anchorage loop 5 and a driving pin 6 disposed at a right angle to said loop. The loop 5 surrounds the shank 4 and is of closed construction, in order that it may not be dissociated from said shank,

notwithstanding that it is movable, both slidably and pivotally, with relation thereto. One of the legs of the loop 5 is bent at a right angle to provide the driving pin 6 5 aforesaid, which driving pin projects from an apex of the loop and has a pointed extremity. An adjoining leg of the loop 5 is suitably articulated with that leg which carries the pin 6 and at the apex whereat the 10 pin joins the loop. Preferably the inner end of the pin 6 is formed with an eye 7 which provides a driving head for the pin and the adjoining leg of the loop 5 has its terminal end bent or coiled, as at 8, through said 15 eye.

Originally the loop 5 is disposed in a plane at a right angle to the plane of the loops 3 and the pin 6 is co-planar with the loops 3 but projects in an opposite direction 20 from the shank 4. This relation of the parts is shown in Fig. 1. With the parts related as described, and prior to the formation of the concrete wall section, the ties are associated with the mold planks C which will 25 adjoin the same side of said wall section as the brick wall section. For this purpose the pins 6 are driven through the mold planks, their heads 7 being struck by the hammer and the operation being precisely similar to 30 that of driving a nail. The loops 3 project into the mold space and are preferably co-planar in order to oppose no obstacle to the blow of the concrete. When the concrete has become sufficiently hard, the mold 35 planks are removed, those designated C being stripped from the pins 6. Thereafter the brick wall section is built up in the usual manner and when a course thereof adjoins a suitable wall tie, the member 2 of such tie 40 is turned pivotally with relation to the member 1 and its loop 5 is positioned upon such course so as to anchor between the same and the course subsequently superposed thereon.

45 Owing to the slidable relation which obtains between the members 1 and 2, the relative elevation of the courses of brick is immaterial. That is to say, it is not essential that the courses between which the loops 50 5 are anchored should occupy absolute planes relatively to the member 1, since the loop 5 may be operatively positioned in any horizontal plane along the length of the shank 4 and consequently the elevation of 55 the courses relatively to the tie may vary. The slidable relation of the members 1 and 2 is also of advantage in that it provides compensation for the expansion, contraction, or other minor displacement of either or 60 both of the sections of which the wall is composed and thus insures that the intrinsic strength of the bond between said sections shall be preserved throughout the life of

the wall, regardless of any normal deterioration thereof.

The practical application of the ties to walls in course of construction is greatly facilitated by the use of a shield, the office of which is threefold; viz., first, to positively maintain the original relation of the 70 members 1 and 2 as above pointed out and as shown in Figs. 1 and 5; second, to take a firm and unyielding bearing against the mold plank through which the pin 6 projects and to positively insure that the members of the tie shall be accurately centered or positioned with reference to the wall sections in which they are to have anchorage; and third, to prevent the cement from interfering with the displacement of the member 80 2 subsequent to the completion of the cement wall section for the purpose of anchoring said member in the brick section. The shield may be of any material suitable for the purposes in view. Fig. 1 shows a composition 85 shield 9, and Fig. 5 shows a metallic shield 9^a. The shield, regardless of its material, is preferably of triangular shape, as shown in Fig. 4. When a composition shield is used, its material surrounds the shank 4, the loop 90 5, and the driving head 7. The driving head is, however, flush with the rear face of the shield in order that its location may be determined. The material employed for the composition shield should be one which, 95 though ordinarily hard or rigid, will soften or partially disintegrate when subjected to moisture. Examples of materials of such character are a mixture of Irish glue and whiting or a mixture of plaster of Paris and 100 sawdust. The composition shield will soften during the formation of the cement wall section, so that when the mold planks C are removed the member 2 may readily be canted for engagement with the brick course, yet 105 notwithstanding its softening or partial disintegration, the shield will prevent the cement from having such access to the shank 4 and the loop 5 as would interfere with either the pivotal or slidable displacement of 110 the member 2 relatively to the member 1. In other words, the shield takes up or defines a certain space or zone in which the shank 4 and driving head 7 are located, and prevents the cement from having access to 115 the space or zone thus defined or set apart. Inasmuch as the cement cannot "set" about the shank 4 or driving head 7, it follows that the member 2 may be moved relatively to said shank, not only for the purpose of 120 the engagement of the loops 5 with the brick wall section, as above explained, but also at any time during the life of the wall, as by reason of any expansion, contraction, or settling of either or both of its sections. In 125 canting the member 2 to effect its anchorage

in the brick wall section, the pin 6 is given a suitably directed blow with a hammer or other implement whereby the loop 5 is moved beyond the shield and thereafter, said 5 loop is manipulated into its anchorage position.

The construction shown in Figs. 5 and 6 is the same as that described, except that the shield 9^a is in the form of a metallic shell.

- 10 In this case the loop 5 originally fits snugly within a marginal flange of said shell, being retained in such position by frictional engagement with said flange. The rear face of the shell may be suitably marked to indicate the position of the driving head 7. If desired, the shield may have at its lower end a prong 10 to provide an additional element for associating the tie with the mold plank C.
- 20 In both constructions in addition to the pin 6, a nail 11 may be employed to associate the tie with the mold plank, such nail being driven through the upper portion of the shield.

- 25 In the original relation of the parts, the loop 5 is parallel to the shank 4 and is preferably arranged above the pin 6 whereby the canting of the member 2, necessary for its anchorage in the brick wall section, may be 30 initiated by a downward blow upon the pin 6.

The construction shown in Fig. 7 is applicable to walls composed wholly of bricks and comprises two members 1^a and 2^a. The member 1^a includes a pair of anchorage loops 3^a and a connecting bar or shank 4^a, and the member 2^a includes a single anchorage loop having at one of its apices an eye 12 which loosely surrounds the shank 4^a 40 whereby the member 2^a may be moved slidably along said shank.

The loops 3^a are in parallel planes and are anchored between different adjoining courses in one of the wall sections, while the loop 2^a is anchored between any pair of adjoining courses of the other wall section. The slideable relation of the member 2^a to the member 1^a provides the same advantages as are secured by this same feature in the 50 constructions previously described.

In certain of the appended claims reference is made to the shield as originally including the anchorage loop of the member 2, and it will be understood that the word "including" is used in such cases in its accepted broad sense, *i. e.*, in the sense of encompassing said anchorage loop.

Having fully described my invention, I claim:

- 60 1. A wall tie comprising a pair of members, each provided with an anchorage loop, one of the members having a shank which extends at a substantial right angle to its

loop and the other member surrounding said shank and being movable lengthwise thereof. 65

2. A wall tie comprising a pair of members one of which is provided with an anchorage loop, and the other of which is provided with a pair of anchorage loops connected by a shank, the first named member 70 surrounding said shank and being movable relatively thereto.

3. A wall tie comprising a pair of members one of which is provided with an anchorage loop, and the other of which is provided with a pair of anchorage loops connected by a shank, the first named member 75 surrounding said shank and being movable lengthwise thereof.

4. A wall tie comprising a pair of members one of which is provided with an anchorage loop, and the other of which is provided with a pair of anchorage loops connected by a shank, the first named member 80 surrounding said shank and being movable slidably and pivotally in the plane thereof.

5. A wall tie comprising a pair of members one of which is provided with an anchorage loop, and the other of which is provided with a pair of anchorage loops connected by a shank, the first named member 85 surrounding said shank and being movable relatively thereto, and having a driving pin, disposed at an angle to its loop and adapted to 90 originally stand out from said shank. 95

6. A wall tie comprising a pair of members one of which is provided with an anchorage loop, and the other of which is provided with a pair of anchorage loops connected by a shank, the first named member 10 surrounding said shank and being movable slidably and pivotally in the plane thereof, and having a driving pin disposed at an angle to its loop and adapted to originally stand out from said shank. 10

7. A wall tie comprising a pair of members one of which is provided with an anchorage loop, and the other of which is provided with a pair of anchorage loops connected by a shank, the first named member 1 surrounding said shank and being movable relatively thereto, and having at one of its apices a driving pin disposed at a right angle to its loop. 1

8. A wall tie comprising a pair of members one of which is provided with an anchorage loop, and the other of which is provided with a pair of anchorage loops connected by a shank, the first named member 1 surrounding said shank and being movable relatively thereto, said first named member also having a leg of its loop bent angularly to provide a driving pin and being formed adjacent its bend with an eye providing a driving head and having an adjoining leg of its loop articulated with said eye.

9. A wall tie comprising a pair of members one of which is provided with an anchorage loop, and the other of which is provided with a pair of anchorage loops connected by a shank, the first named member surrounding said shank and being movable relatively thereto, said first named member also having at one of its apices a driving pin disposed at a right angle to its loop, and a shield inclosing said shank and originally inclosing the loop of the member which is movable relatively to said shank. 65
10. A wall tie comprising a pair of members one of which is provided with an anchorage loop, and the other of which is provided with a pair of anchorage loops connected by a shank, the first named member surrounding said shank and being movable relatively thereto, said first named member also having at one of its apices a driving pin disposed at a right angle to its loop, and a composition shield inclosing said shank and originally inclosing the loop of the member which is movable relatively to said shank. 75
11. A wall tie comprising a pair of members movable pivotally with relation to one another and each having an anchorage loop and a shield originally inclosing the anchorage loop of one of the members. 80
12. A wall tie comprising a pair of members movable pivotally with relation to one another and each having an anchorage loop and a composition shield originally inclosing the anchorage loop of one of the members. 85
13. A wall tie comprising a pair of members movable pivotally with relation to one another and each having an anchorage loop, one of the members having a driving pin disposed at a right angle to its loop and a shield originally inclosing the loop of the member which has the driving pin. 90
14. A wall tie comprising a pair of members movable pivotally with relation to one another and each having an anchorage loop, one of the members having a driving pin disposed at a right angle to its loop and a composition shield originally inclosing the loop of the member which has the driving pin. 95
15. A wall tie comprising a pair of members, one of which is provided with co-planar anchorage loops and a shank connecting said loops and the other of which is provided with an anchorage loop surrounding said shank and having a driving pin projecting angularly from one of its apices. 100
16. A wall tie comprising a pair of members one of which is provided with co-planar anchorage loops and a shank connecting said loops and the other of which is provided with an anchorage loop surrounding said shank and having a driving pin projecting angularly from one of its apices, and a shield inclosing said shank and originally inclosing the loop of the member which is provided with the driving pin. 105
17. A wall tie comprising a pair of members, one of which is provided with co-planar anchorage loops and a shank connecting said loops and the other of which is provided with an anchorage loop surrounding said shank and having a driving pin projecting angularly from one of its apices, and a composition shield inclosing said shank and originally inclosing the loop of the member which is provided with the driving pin. 110
18. A wall tie comprising a pair of members each provided with an anchorage loop and movable pivotally with relation to one another, one of the members having a driving pin disposed at a right angle to its loop. 115
19. A wall tie comprising a pair of members each provided with an anchorage loop and movable pivotally with relation to one another, one of the members having a driving pin projecting from an apex of its loop and at a right angle to said loop. 120
20. A wall tie comprising a member constructed for anchorage in a wall section, a second member movably associated with said first named member and having a driving pin, the second member being constructed for anchorage in a second wall section adjoining said first named section, and a shield originally inclosing the second member and from which the driving pin originally projects. 125
21. A wall tie comprising a member constructed for anchorage in a wall section, a second member movably associated with said first named member and having a driving pin, the second member being constructed for anchorage in a second wall section adjoining said first named section, and a composition shield originally inclosing the second member and from which the driving pin originally projects. 130
22. A wall tie comprising a member constructed for anchorage in a wall section, a second member pivotally movable relative to said first member and constructed for anchorage in a wall section adjoining said first wall section, and a shield originally inclosing said second member. 135
23. A wall tie comprising a member constructed for anchorage in a wall section, a second member pivotally movable relative to said first member and constructed for anchorage in a wall section adjoining said first wall section, and a composition shield originally inclosing said second member. 140
24. A wall tie comprising a member having a pair of anchorage loops and a shank connecting said loops, a second member comprising an anchorage loop surrounding said shank, and a shield originally inclosing the

loop of said second member and holding said loop in a plane parallel to the plane of the wall.

25. A wall tie comprising a member having a pair of anchorage loops and a shank connecting said loops, a second member comprising an anchorage loop surrounding said shank, and a composition shield originally inclosing the loop of said second member

and holding said loop in a plane parallel to 10 the plane of the wall.

In testimony whereof I have hereunto set my hand in presence of two subscribing witnesses.

FRANCIS W. GARTRELL.
